INVENTOR
August M. Becker
BY C. P. Gospel
ATTORNEY

UNITED STATES PATENT OFFICE.

AUGUST M. BECKER, OF NEW YORK, N. Y.

CAN OPENER.

Application filed July 29, 1924. Serial No. 728,810.

To all whom it may concern:

Be it known that I, AUGUST M. BECKER, a citizen of the United States, resident of New York, in the county of New York, State of New York, have invented certain new and useful Improvements in Can Openers, of which the following is a specification.

This invention relates to can openers, and more particularly to that type of cans in which the can cover is adapted to be attached or detached from the body of the can so as to enable the cover of the can to be used again and again, that the cover of the can is not torn open as is sometimes the case with can openers.

The object of my invention is to provide a very simple means which may be readily made with substantially one manufacturing operation, and my further object is to provide a can opener which is simple in construction so as to facilitate the opening of the can and also the carrying of the can opener by the user.

It is well known that cans consisting of a bottom and cover portion, which are usually used for shoe blacking, pomades, creams, ointments and the like, have the cover so securely fastened to the body of the can as to make it well nigh impossible for the ordinary user to remove the cover from the body of the can. Such frictional hold results sometimes from the lack of proper registration between the body of the can and cover, and at other times due to a certain rusting of the metal, or to other causes well known to the users of cans of this type, and if the cover be distorted by the use of any implement not especially adapted for the purpose, such distortion of the cover while it may permit the ready removal of the cover from the body of the can renders a still tighter connection between the body of the can and the cover is again placed on the body of the can. To overcome these objections I provide a very simple can opener consisting essentially of a main member having thereon two oppositely disposed lever members, both of said lever members being adapted to insert in the usual crack between the edge of the cover and the body of the can, and by the very slight turning movement of said main member the opposite disposed lever members serve to raise the cover from the body of the can.

The invention will be more fully described

hereinafter shown in the drawing and finally pointed out in the claims.

In the accompanying drawing,—

Figure 1 is a perspective view of a can having its cover thereon and my improved can opener placed in position in respect thereto, as it is desired to use the can opener when it is desired to open the can cover;

Figure 2 is a detailed section of a part of the can and cover with my invented can opener applied thereto, showing the cover in the process of removal from the body of the can;

Figure 3 is a plan view of my can opener;

Figure 4 is an end view of the same, and

Figure 5 is an end view taken at right angles to that of Fig. 4.

Similar characters of reference indicate the corresponding parts throughout various views.

Referring to the drawings, and more particularly to Figs. 3, 4 and 5, my improved can opener consists of a main portion 10 having a suitable handle 11 preferably as shown in the drawings integral therewith and at one edge of the main member 10 there is arranged a circular cutout 12. At either side of this circular cutout 12 a lever member 13 and a second lever member 14 is provided. These lever members are so constructed as to be, each bevelled off at one side, whereas the other side of each lever member is flat or flush with the surface of the main member 10. So, for instance, the bevelled portion 15 of the member 13 extends from the flush portion 16 in bevelled form until said bevel fuses in with the flat surface of the main member 10, said flat surface being opposite to the surface around the flat portion 16 is arranged. The other member 14 is identical with the member 13 excepting that it is oppositely disposed. In the member 14 the flat surface 17 is flush with the side 18 of the member 10, and the bevelled portion 19 begins at the flat surface 17 and covers over into the flat surface 20 of the member 10. The recess extends between the members 13 and 14 as shown by 12 in Fig. 4.

In the use of my improved can opener the portion 10 is placed between the cover portion 21 and the body portion 22 of any suitable can. It is common practice in cans of this kind to provide the body portion 22

105

110

with a seat 23 against which the cover portion 21 rests and which seat usually determines the range of movement of the cover portion. When the cover is thus placed on 5 the seat 23 and the can is closed and it is adapted to open the can cover 21 and remove it from the body portion 22, then the member 10 is inserted into the crack between the cover and the seat 23, and the handle 10 11 is given a turning movement in the direction of the arrows 24. This turning movement causes the flat surface 16 to press against the edge of the cover 21 and the other flat surface 17 to press against the seat 23. Thereby a very efficient opener is 15 provided, the bevelled portions 15 and 19 permit the ready insertion of the two lever members 13 and 14 into the relatively fine crack between the cover 21 and the body portion 22, the recess 12 enabling such insertion to be readily made.

20 I have described one embodiment of my invention, but it is clear that changes may

be made in the details thereof without departing from the spirit of my invention as 25 defined in the appended claim.

I claim:

An improved can opener, comprising a main member, a handle on said main member, two lever members on the main member at opposite sides thereof, all of said members being of one single piece and integral with each other, each of said lever members having a flat portion flush with one surface of the main member and another portion bevelled off from said flat portion to the oppositely disposed surface of said main member and having a recess between the two lever members curved inwardly from one, across and outwardly to 40 the other.

In testimony that I claim the foregoing as my invention, have signed my name hereto.

AUGUST M. BECKER.
